(57) **CLAIM**

The ornamental design for a dispensing cap, substantially as shown and described.

DESCRIPTION

FIG. 1 is a perspective view of the dispensing cap showing the new design;

FIG. 2 is a front of the dispensing cap showing the new design;

FIG. 3 is a left side view of the dispensing cap showing the new design;

FIG. 4 is a right side view of the dispensing cap showing the new design;

FIG. 5 is a rear view of the dispensing cap showing the new design;

FIG. 6 is a top view of the dispensing cap of FIG. 1 showing the new design; and,

FIG. 7 is a bottom view of the dispensing cap of FIG. 1 showing the new design.

The broken lines depict portions of the dispensing cap that form no part of the claimed design.

1 Claim, 7 Drawing Sheets
